SIGN MOUNTING MEANS FOR A VEHICLE
BUMPER
Warren S. Hastings, 202 N. Front St., Mounds, Ill.
Filed Nov. 27, 1963, Ser. No. 326,417
3 Claims. (Cl. 40—129)

This invention relates to a sign mounting means for vehicle bumpers.

An object of the present invention is to provide a sign mounting means which enables the ready attachment of a sign to a vehicle bumper, and which permits the sign, when attached to the vehicle bumper, to be swung between an upright or use position and a lay-down position.

Another object of the present invention is to provide a sign mounting means which lends itself to supporting a sign in an upright or use position from a vehicle bumper, and permits the sign to be released from the upright position and swung to a lay-down position, and which may be swung from the lay-down position to the upright position and releasably retained in the upright position.

A further object of the present invention is to provide a sign mounting means which is capable of ready attachment to or detachment from a vehicle bumper, and which is highly efficient in action, and commercially feasible.

Other objects and advantages of the present invention will become apparent from the following description taken in conjunction with the accompanying drawings, in which:

FIGURE 1 is an elevational view of the rear portion of an automobile with the sign mounting means of the present invention attached to the bumper of the automobile and with the sign supported in the mounting means, the full-line showing illustrating the sign in lay-down position for access to the trunk, and the dotted-line showing illustrating the sign in upright or use position.

FIGURE 2 is an enlarged sectional view taken on the line 2—2 of FIGURE 1.

FIGURE 3 is a fragmentary sectional view taken on the line 3—3 of FIGURE 2.

FIGURE 4 is a view of the assembly of FIGURE 3, with parts broken away, showing the post in upright or use position.

FIGURE 5 is a sectional view taken on the line 5—5 of FIGURE 4.

FIGURE 6 is a sectional view taken on the line 6—6 of FIGURE 5.

FIGURE 7 is an exploded view of the mounting means of the present invention.

Referring to FIGURE 1 of the drawings, a pair of sign mounting means of the present invention and indicated generally by the numeral 10, are shown mounted upon a bumper 12 of an automobile 14, the pair of means receiving the sign supporting post 16 of a sign-containing frame or sign 18.

Inasmuch as the two sign mounting means 10 are identical in structure, only the right-hand one will be specifically described. Such means comprises a saddle 20 which is positioned so as to rest upon and be supported upon the top portion of the bumper 12. Disposed in spaced relation to the saddle 20 is a backing member 22, the backing member being fixedly attached to a socket 24 which extends along one face thereof. As shown in FIGURES 2 and 7, the socket 24 is in the form of an open-ended sleeve which sleeve abuts against a face of the backing member 22 and is fixedly attached to the backing member by means of a threaded bolt 26 extending through a threaded hole 27 formed in the backing member 22, and also a threaded hole 28 formed in the socket or sleeve 24, the bolt being fixedly held in place through the medium of a threaded lock nut 29 in threaded

2

engagement with the threaded bolt 26 and in bearing engagement with the inner face of the socket or sleeve 24.

Means is provided for fixing the socket or sleeve 24 in position on the backing member 22, such means comprising a U-shaped tie bar 30 whose bight 31 is disposed so as to embrace the socket or sleeve 24 with its legs 32 extending through spaced apertures 33 also provided in the backing member 22, the projecting end portions of the legs being threaded and being fixedly and tightly secured to the backing member 22 by means of threaded lock nuts 35 in threaded engagement with the threaded projecting end portions of the legs 32 and bearing against the other face of the backing member 22.

A horizontally-disposed pivot means connects the backing member to the saddle 20 for swinging movement of the backing member about the pivot means to a position in which the socket 24 extends in an upright position or direction. Specifically, the pivot means comprises a pair of spaced aligned horizontally-disposed pivot pins 36, the pins 36 being carried by a pair of legs 37 rising from the ends of the saddle 20 and on these pins 36 are rotatably mounted lugs 38 which project from the side edges of the backing member 22.

At least two ears 40 are each supported on the pivot means for rocking movement therearound. Specifically, each ear 40 is supported on a pivot pin 36 for rocking movement therearound by means of a knuckle 41 which is on the ear and which is rotatably supported on the pivot pin 36.

It is to be noted that the pins are each in the form of a threaded bolt and to adjustably retain the lugs 38 of the backing member 22 and the knuckles 41 of the ears 40 on the threaded bolt, a threaded lock nut 56 is in threaded engagement with each of the threaded bolts 36 and is turned down until it tightly engages the adjacent lug 38 of the backing member 22.

A fastening element 43 extends through and is adjustably securable to each of the ears 40 and has means on one end which is adapted to embracingly engage an edge of the top portions of the bumper 12 when the saddle 20 is positioned on the top portion of the bumper 12. Specifically, the fastening element 43 embodies a threaded shank 44 which extends loosely through a hole 45 provided in each of the ears 40 and a hook 46 on one end which is adapted to embracingly engage an edge of the top portion of the bumper 12 when the saddle 20 is positioned on the top portion of the bumper 12, the threaded shank 44 being adjustably secured to the adjacent ear 40 by means of a threaded nut 48 in threaded engagement with the shank 44.

Strap means, indicated generally by the numeral 49, is carried by the saddle 20 and has a free end provided with means which is adapted to embrace a lower end edge of the bumper 12 when the saddle 20 is positioned upon the top portion of the bumper 12 to hold the saddle in position on the bumper 12 of the vehicle 10. Specifically, the strap means 49 embodies a chain 50 which has one end attached to a side edge of the saddle 20, as at 51, and which has the other or free end provided with a hook 52 which embraces the lower end edge of the bumper 12 when the saddle 20 is positioned upon the top portion of the bumper 12.

An articulated support member 60 is arranged in an upright direction and has the lower end portion extending into and secured to the socket 24 and has the upper end portion swingable from the upright direction, as shown in dotted lines in FIGURE 2, to a downward direction, as shown in full lines in FIGURE 2. Specifically, the lower end portion of the support member 60 embodies a short tube 61 which is disposed within and is firmly secured to the socket 24 by means of the bearing contact of the tie bar 30 with the socket or sleeve 24. The upper

end portion of the support member 60 embodies an elongated pipe 62 provided with a longitudinal slot 63, the purpose of which will subsequently become apparent. The pipe 62 is pivotally connected to the tube 61 as by laterally-spaced link bars 64 which are pivotally connected at their complementary ends to the pipe 62 and tube 61 respectively.

One of the sign supporting posts 16 for the display sign has a lower end portion circumscribed about and connected to the upper end portion or pipe 62 of the articulated support member 60 for sliding back-and-forth movement thereon. Specifically, the lower end portion of the post 16 is connected to the pipe 62 by a pin 65 projecting from the interior of the lower end portion of the post and slidably engaging the slot 63 of the pipe 62. The lower end portion of the post 16 is telescopically and releasably received in the socket 24 and has its lower end resting upon the upper end of the tube 61 when the articulated support member 60 is in the upright direction for holding the post 16 in the upright direction or upright position.

In operation, with a sign attached to a pair of spaced sign mounting means and the articulated member 60, the sign supporting post 16, and the sign in a lay-down position, one of the sign supporting means of the present invention is positioned so that the saddle is upon the top portion of the bumper 12 of the vehicle 10, and the hook 52 of the chain 50 is then placed so that it embracingly engages the lower end edge of the bumper 12. The nuts 56 are then loosened from the pivot bolts 36, the backing member 22 swung to a position such that the socket 24 is in the upright direction, and the ears 40 swung to a position such that the hooks 46 of the threaded shanks 44 engage the edge of the top portion of the bumper 12, whereupon the nuts 56 are then tightened against the lugs 38 on the backing member 22. The other sign mounting means of the present invention is similarly mounted upon the bumper 12 of the vehicle 10. The articulated members 60, the post 16, and the sign 18 carried thereby are then swung so that the members are in upright position, whereupon the lower end portions of the posts are slid along the adjacent pipe 62 toward the adjacent sockets 24 until the lower ends of the posts 16 are telescopically received within and rest upon the upper ends of the tubes 61 of the articulated members 60, resulting in releasably holding the posts 16 and the associated sign 18 in the upright or use position. To swing the sign 18 to the lay-down position, the lower end portions of the posts 60 are shifted upwardly until they are free of the sockets 24 and encompass the pipes 62 of the articulated members 60, whereupon the pipes 62 of the articulated members 60 are pivotally connected at their complementary ends to the pipe 62 and tube 61 respectively.

What is claimed is:

1. A sign mounting means for a vehicle comprising a

saddle adapted to be positioned so as to rest upon and be supported upon the top portion of a bumper of a vehicle, a backing member, a socket extending along one face of and fixedly attached to said backing member, said backing member being disposed in spaced relation to said saddle, horizontally-disposed pivot means connecting said backing member to said saddle for swinging movement of said backing member about said pivot means to a position in which said socket extends in an upright direction, at least two ears each supported on said pivot means for rocking movement therearound, a fastening element extending through and adjustably securable to each of said ears and having means on one end adapted to embracingly engage an edge of the top portion of a bumper of a vehicle when said saddle is positioned on the top portion of the bumper of said vehicle, strap means carried by said saddle and having a free end provided with means adapted to embrace the lower end edge of a bumper of a vehicle when said saddle is positioned upon the top portion of the bumper of said vehicle to hold the saddle in position on the bumper of said vehicle, an articulated support member arranged in an upright direction and having the lower end portion extending into and secured to said socket and having the upper end portion swingable from the upright direction to a downward direction, and a sign supporting post for a display sign having the lower end portion circumscribed about and connected to the upper end portion of said support member for sliding back-and-forth movement thereon, said lower end portion of said post being telescopically and releasably received in said socket when the articulated support member is in the upright direction for holding said post in the upright direction.

2. The sign mounting means according to claim 1 wherein the lower end portion of said articulated support member embodies a tube, and the upper end portion of said articulated support member embodies an elongated pipe which is pivotally connected to said tube.

3. The sign mounting means according to claim 2 wherein the pipe is pivotally connected to the tube of the articulated support member by laterally-spaced link bars pivotally connected at their complementary ends to said pipe and tube respectively.
